UNITED STATES PATENT OFFICE.

EMILE AIMOND, OF PARIS, FRANCE.

ELASTIC WHEEL.

1,155,865.

Specification of Letters Patent.

Patented Oct. 5, 1915.

Application filed August 8, 1912. Serial No. 714,026.

To all whom it may concern:

Be it known that I, EMILE AIMOND, a citizen of the Republic of France, residing at Paris, 21 Rue Chaptal, in the Republic of France, engineer, have invented certain new and useful Improvements in an Elastic Wheel, of which the following is a specification.

This invention relates to elastic wheels of 10 the type in which the hub is suspended within a rigid rim by means of an internal ring which can yield relatively to the hub and to the rim and is connected to these parts by two series of radially arranged 15 springs.

The invention consists in an improved elastic wheel of this type in which the play of the yielding ring relatively to the rim is small, so that the springs between 20 these two parts have the sole function of pressing the spokes against bearing plates on the rim, the elasticity of the suspension being insured by other springs inserted between the yielding ring and the hub.

25 The play allowed between the yielding ring and the hub corresponds to the maximum vertical displacement of the axle.

The springs between the ring and the rim act on telescopic spokes one end of which 30 bear against the uniform surface of the ring and the other against bearing plates on the rim, which spokes are guided radially in bearings attached to the hub incapable of turning relatively thereto. Owing to this 35 guiding and the pressure of the spokes against the bearing surfaces of the rim the torque is transmitted from the hub to the spokes and from the spokes to the rim, or inversely from the rim to the hub.

40 Owing to this division of the functions of the two sets of springs each of these may be adapted to the work it has to perform and the pressure of the telescopic spokes against the rim can be maintained continuously along the whole circumference, insuring 45 a powerful and silent drive, without wear.

One construction of the improved elastic wheel according to the present invention is 50 illustrated in the accompanying drawings, in which—

Figure 1 illustrates a portion of the wheel, partly in elevation and partly in section. Fig. 2 is a transverse section at the line 55 A—A of Fig. 1. Figs. 3 and 4 are diagrams illustrating the working of the wheel.

In this construction the hub a consists of two sleeves a^1 and a^2 one fitting in the other and provided with parallel flanges a^3 , and two cheeks a^4 of annular form, the internal 60 and external edges of which bear the one against the other respectively, and of which the middle parts are cut away, leaving a certain space between the cheeks; these cheeks are securely bolted to the flanges a^3 . 65

b denotes the rim of the wheel consisting for example of a ring b^1 of U-shaped section, two rings b^2 attached to the ring b^1 by means of angle pieces b^3 and bolts b^4 , and a rubber tire b^5 . Within this rigid rim are 70 fixed by means of bolts b^6 , bearing plates b^6 having a concave side turned toward the center of the wheel, these plates serving for the transmission of the torque. In the space between the cheeks a^4 is located the yielding 75 ring c the periphery of which is uniform. This ring is attached to the rim by means of a series of telescopic spokes d consisting of two sleeves d^1 , d^2 sliding one in the other and inclosing a spring e tending to hold 80 them apart and press their ends provided with rollers d^4 and d^5 against the ring c and the bearing plates b^6 of the rim. The sleeves d^1 are guided radially in bearings a^5 85 fixed rigidly in the outer flanges of the cheeks a^4 . These bearings are of as large diameter as permitted by the play allowed between the axle and the hub, and the rim, so that the spokes are comparatively little 90 out of true beyond the bearings a^5 and are only slightly stressed by the transmission of circumferential forces. The elasticity of the suspension is derived from springs f encircling the spokes and compressed between 95 the bearings a^5 , attached to the hub, and the bottom flanges d^6 of the sleeves d^2 , the rollers d^5 of which continuously bear against the yielding ring c . 100

Under the effects of the load on the hub the springs f in the upper half of the wheel are compressed (Fig. 4) and push down the rings c . In the lower half of the wheel the spokes are compressed by the ring c , but they cannot yield far in this direction since the clearance between the ends of the sleeves d^1 and the bottoms of the sleeves d^2 is small so that the load is then directly transmitted by the spokes from the ring c to the bottom of the rim b ; the elasticity 105 of the suspension is thus given exclusively by the springs f . The springs e keep the rollers d^4 and d^5 always in contact with the 110

ring c and the bearing plates b^6 of the rim with sufficient pressure to insure the driving of the rim by the spokes, or of the spokes by the rim, according to circumstances. The play of the sleeves d^1 and d^2 relatively to each other is such that the rollers d^4 and d^5 are never compelled to leave the ring c or the plates b^6 , so that there is freedom from shock noise and wear.

10 The above described constructional arrangements give a wheel of simple and strong construction. The details may be modified without departure from the invention.

15 The wheel illustrated is provided with sheet metal cheeks g g^1 fixed to the rim and to the hub respectively, packing pieces g^2 being provided where the cheeks work on each other. The cheeks g may be attached to the sides of the ring b^1 by means of, for example, narrow rings g^3 held in place and pressed against the cheeks by suitable claws g^4 which pass through the bolts b^4 . In Fig. 2 a bearing plate b^6 and 20 a claw g^4 are shown secured by the same bolt b^4 , but the plate and claw may be secured by separate bolts.

I claim—

30 1. An elastic wheel comprising the combination of a hub, a rigid felly having internally angular parts, a free ring, springs radially arranged between the free ring and the hub, telescopic spokes interposed between the free ring and the angular surfaces of the felly, and springs located in the telescopic spokes and adapted for lengthening the latter.

40 2. An elastic wheel comprising the combination of a hub having guiding parts, a rigid felly having internally angular parts, a free ring, springs radially arranged between the free ring and the hub, telescopic spokes interposed between the free ring and the an-

45 gular surfaces of the felly, and springs located in the said telescopic spokes and adapted for lengthening the latter, such spokes being radially guided in said guiding parts and those guiding parts being placed as near as possible to the felly to allow the necessary play of the hub with respect to the 50 felly.

3. In an elastic wheel the combination of a hollow hub, a free ring within the hollow hub, a rigid felly having internally angular parts, telescopic spokes which are radially 55 guided in the periphery of the hub, their outer ends bearing against the angular surfaces of the felly and their inner ends bearing against the periphery of the free ring, springs located in the said telescopic spokes 60 and adapted for lengthening the latter, and springs interposed between the said free ring and the peripheral part of the hollow hub.

4. A yielding wheel comprising the combination of a rigid felly having angular 65 inner parts, a hub, a free ring independent of the felly and of the hub, yielding spokes having springs compressed between the angular parts of the felly and the said ring and so adapted as to allow only a little radial play on the part of the ring with respect to the felly, and springs intercalated between the said ring and the hub, the radial play of the hub with respect to the 70 ring, and consequently, the play of the springs intercalated between them, being greater than that of the ring with respect to the felly.

5. In testimony, that I claim the foregoing 80 as my invention I have signed my name in presence of two subscribing witnesses.

EMILE AIMOND.
